RAIL DERRICK

Royce Kershaw, Montgomery, Ala.

Application May 10, 1946, Serial No. 668,813

7 Claims. (Cl. 254—139.1)

1

This invention is a rail derrick adapted particularly for use in railroad construction and reconstruction for the quick and easy handling of various machines and materials used in such work.

The primary object of the invention is to provide a rail derrick in connection with a supporting vehicle of light construction capable of being quickly and easily removed from the track after its purposes have been fulfilled, or to permit of railway cars passing over a track under reconstruction.

A further object of the invention is to provide a derrick in association with a supporting car, wherein the load to which the derrick is subjected is borne directly by the rail and is not transmitted to the car.

A further object of the invention is to provide a derrick of the character and for the purposes generally stated involving a construction whereby the derrick may be easily and quickly taken apart or dismantled, or may with facility be erected and ready for operation at either side of the car.

A further object of the invention is to provide a vehicle supported derrick structure with improved means for dogging the supporting car to the rails for stabilizing purposes.

With the foregoing objects in view, together with others which will appear as the description proceeds, the invention consists in the novel construction, combination and arrangement of parts, all as will be described more fully hereinafter, illustrated in the drawing, and particularly pointed out in the claims.

In the drawings—

Fig. 1 is a side elevation of a rail derrick constructed in accordance with the invention and illustrating the parts in the position they will assume when the derrick is ready for operation,

Fig. 2 is a top plan view of the improved derrick and associated structure, and

Fig. 3 is an end elevation on an enlarged scale, showing the supporting car and the manner in which it may be dogged to the rails.

In carrying out the invention, the vehicle proposed includes a light body or frame indicated at 4, which, as here shown, may be made of channel members of light but durable construction bolted or welded together in substantially rectangular form and suitably braced in order that it may withstand strains and stresses to which it may be subjected in use and handling. The body frame of the vehicle carries transversely disposed axles 5 near its ends to which are secured track-engaging wheels 6, the latter being spaced apart

2

the standard gauge to rest and travel upon the rails indicated at 7. It is preferred that this vehicle be of such size and such weight as will enable the same to be readily lifted by workmen 5 to be applied to or removed from the track as occasion requires.

The derrick structure associated with the vehicle includes a mast 8 which may be formed of metal of light gauge for convenient handling, this mast having a bracket 9 secured near its lower end and to which the pivot pin 10 of a boom 11 may be removably secured. This boom may be of appropriate length, gauge and weight for the uses to which it will be subjected. The 10 outer end of the boom is provided with a sheave or pulley 12 over which a rope or cable 13 passes, the inner end of which is secured to a drum or hoist mechanism 14 carried by the boom. This drum may be rotated by hand if desired, or it 15 will be understood that a power-operated drum may be employed if desired. The boom is stabilized by a rod 15 detachably connected at one end as at 16 to the boom and by means of the key and slot connection indicated at 17 at its 20 inner end. This key engages in a slot or opening provided in the forwardly extending clevis member 18 at the top of the mast. From this construction it is apparent that the boom is 25 capable of swinging in an arc upon the upstanding mast 8, and that operation of the windlass or drum 14 enables articles, machinery or supplies 30 to be readily lifted by the boom.

The mast 8 is provided near its lower end with a depending member constituting a tongue 19, 35 which tongue is engageable in a clevis member or socket 20 on the end of the car body 4 directly above the rails 7. It will be observed that a clevis or socket member 20 is provided at each side of the car so that the mast may be erected over either of the supporting rails 7 of the track. The 40 tongue and socket elements are so located that when the tongue is properly engaged with the socket the lower end of the mast is either engaged with the underlying rail or is spaced a fractional distance above it, so that weight delivered to the mast through the boom 11 will be borne by the rail 7, rather than by the frame or body of the car. It is also to be observed that the pivotal connection of the boom with the mast is in approximately 45 the same horizontal plane with the body of the car, so that the weight of the boom will tend to hold the mast securely in place against the car end.

The mast is equipped with means for maintaining it in properly stabilized upright position,

which means includes guy rods 21. These rods have their ends flattened as shown, their upper ends being secured by means of readily assembled pins 22 between outwardly projecting ears 23 secured to the upper end of the mast. The lower ends of the rods are engaged between and pinned as at 24 between spaced ears projecting upwardly from the car body at the corners thereof. One of the rods 21 is disposed transversely of the car as shown more particularly in Fig. 2, while the other is disposed longitudinally of the car and parallel with the sides thereof. To additionally stabilize the mast, a diagonal tie rod or brace 25 is used. This rod has its upper end hooked within an ear 26 projecting laterally from the upper end of the mast 8, while its lower end is similarly hooked within an upstanding ear 27 on the car frame diagonally opposite the corner which supports the mast. The connection of these stay or guy rods with the mast and car is such that while they afford rigid stabilization for the mast, they may be quickly and easily detached and the entire derrick structure dismantled when occasion requires. The arrangement and assembly is also such that the mast may be erected at either side of the car so that the mast is not confined to use at one side only of the car body.

The invention also comprehends improved means for dogging or clamping the car body to the rails when the derrick or crane is to be used. The mechanism for accomplishing this clamping action includes a rock or oscillatory shaft 28 mounted longitudinally and preferably in the median line of the car body, suitable bearings 29 being employed to properly support the shaft. Depending from each of the four corners of the body frame of the car are links 30, the said links being pivoted to the underside of the car frame by pins 31 passing through ears secured to the car frame. Clamp members 32 are pivoted at their upper ends as at 33 to the lower ends of links 30. The members 32 are provided at their lower ends with inturned head members 34 to engage beneath the ball of the rail 7.

The shaft 28 is provided near its ends with radially disposed arms 35, to the outer ends of which links or rods 36 are pivotally attached. These rods are also pivotally engaged at their outer ends with the pivot members 33 connecting links 30 with clamp members 32. The rods 36 may be adjustable lengthwise for obvious purposes, the nut and thread arrangement represented generally at 37 being employed for this purpose.

Pivoted mounted upon the car body for rocking movement transversely thereof is a lever 38, the pivotal connection with the car frame being represented at 39. The lower end 40 of this lever is pivoted as at 41 to the outer end of a link or connecting rod 42, the inner end of which is connected as at 43 with an arm 44 secured to and radiating from the rock shaft 28. The rod or link 42 may also be adjusted longitudinally by operation of the nut 45 as will be understood.

From the foregoing description it is obvious that the car body, of simple construction and light weight, may be easily lifted and placed upon the rails 7 when desired and may with equal facility and ease be removed therefrom when required. In construction and reconstruction operations, when it is desired to lift heavy machinery or supplies the mast is erected at that side of the car most convenient to the materials or weights to be handled. With the mast erected

and stabilized in the manner described, the windlass may be operated to lift the machines and materials and the weight thereof is borne entirely by the mast which rests directly upon the supporting rail. None of this excessive weight is delivered to the framing or body of the car. In order that the car may be held rigid against any tendency toward moving while the derrick is in operation, as well as to maintain the car against any tendency toward tipping, the dogging mechanism is employed. The mechanism, as described, is of extremely simple construction and is easily operated to bring about a secure and rigid clamping action between the car and the rails 7. Movement of the operating lever 38 in one direction causes the links 30 to be swung in such direction as will bring about upward movement of the clamps 32, causing a rigid binding between the heads 34 thereof and the underside of the ball portions of the rails 7. Movement of the lever 38 in the opposite direction will cause a breaking of this clamping action whereupon the car may be moved along the track or removed therefrom if desired. From the foregoing, it is apparent that I have provided a portable and readily handled derrick structure of extremely simple construction, which may be easily handled with but few workmen, which has its parts so constructed and assembled as to be capable of being easily erected or dismantled with the exercise of a minimum of skill, and which will prove thoroughly efficient and practical in accomplishing the ends sought.

Having thus described my invention, I claim:

35 1. In a derrick structure, a vehicle including a frame, a socket on said frame, a mast engaged with said socket and adapted to rest upon the support for the vehicle, said mast bodily removable from said vehicle, guy members releasably connecting the mast to said frame, and means for holding said vehicle upon its support.

2. In a derrick structure, a vehicle comprising a car body adapted to travel upon a track, a mast removably mounted at one corner of said body and resting upon a rail of said track, guy members releasably connecting said mast with other corners of said body, and a crane supported by said mast.

3. In a derrick structure, a vehicle comprising a car body mounted upon wheels and adapted to travel upon a track, a socket at a corner of said body disposed directly above a rail of said track, a mast bodily removable from and engaged with said socket and resting upon said rail, a boom pivoted to said mast in substantially the same horizontal plane with said car body, a brace connecting the outer end of said boom with the upper part of said mast, and guy rods connecting the top of said mast with other corners of said car body.

4. In a derrick structure, a vehicle comprising a car body adapted to travel upon a track, socket members on said body disposed one directly above each rail of said track, a mast, a tongue offset from said mast to engage in either of said socket members while resting upon a rail, guy rods removably connecting the upper part of said mast with said car body, and a crane carried by said mast.

5. In a derrick structure, a car body having wheels to travel upon a track, a rock shaft disposed longitudinally and substantially centrally of said car body, links pivoted to and depending from said car body above said rails, clamps pivoted to said links and having portions to engage with

said rails, arms connected to and projecting from said rock shaft, rods connecting said arms with the lower ends of said links, and a lever for rocking said shaft.

6. In a derrick structure, a car body to travel upon track rails, socket members at opposite corners of said body disposed above said rails, a mast, a tongue secured to said mast engageable in either of said socket members, said tongue disposed a distance above the bottom of the mast equal to the distance from the sockets to the rails whereby said mast will rest upon a rail when the said tongue is engaged in a socket, guy rods detachably connecting the upper end of said mast with corners of said vehicle, and lifting mechanism carried by said mast.

7. A car body having wheels to travel upon a track, a rock shaft disposed centrally and longitudinally of said body, links pivoted at their upper ends to said body above said tracks, clamp members pivoted at their upper ends to the lower ends of said links, rail engaging heads at the lower

ends of said clamp members, arms connected to and projecting from opposite sides of said rock shaft, rods connecting the ends of said arms to the pivots connecting said links and clamp members, and a lever for rocking said shaft.
